UNITED STATES PATENT OFFICE.

ELLIS E. THOMPSON, OF CEDAR RAPIDS, IOWA.

BURGLAR-PROOF SAFE.

1,113,507.

Specification of Letters Patent.

Patented Oct. 13, 1914.

Application filed September 15, 1913. Serial No. 789,790.

To all whom it may concern:

Be it known that I, ELLIS E. THOMPSON, a citizen of the United States, residing at Cedar Rapids, in the county of Linn and 5 State of Iowa, have invented certain new and useful Improvements in Burglar-Proof Safes, of which the following is a specification.

The object of this invention is to improve 10 the construction of safes of the solid, cast steel type, and more particularly the doors of such safes, so as to render them less vulnerable to attacks by burglars, especially through the use of high explosives.

15 The nature of the invention is fully disclosed in the description and claims following, references being had to the accompanying drawings, in which—

Figure 1 is a central, vertical section of a 20 safe embodying my improvements. Fig. 2 is a front view of the same with a fragment of the base. Fig. 3 is a rear or inner view of the revolving portion of the door. Fig. 4 is a section of the same on the line *a b* of Fig. 1, looking toward the front. Fig. 5 is a similar section, looking 25 toward the rear. Fig. 6 is a fragmentary section of the safe, in the line *c d*, looking toward the front.

30 In the drawings 1 denotes a safe of the solid, cast-steel, nearly spherical type, mounted on a base 2. In the front of the safe is mounted a circular door, 3 of the breech-block type, having lugs 4 adapted to engage corresponding lugs 5 forming a part 35 of the door-jamb 6. The interlocking part of the door is mounted revolvably in a circular frame 7, in a familiar way, and is turned to interlock the lugs by means of a spider 8 40 in the usual way. This frame is provided with lugs 9, to which is pivoted a yoke 10 hinged at 11 to lugs 12 extending from the body of the safe in front.

The improvement in the door consists in 45 providing it with a cavity 13, preferably about in line with the inner shoulder 14 of the jamb. This should be formed by means of a core as the door is cast. The radial extensions of the cavity, which form the supports for the core, are preferably made to 50 terminate at the shoulder 15 of the door, and to open inwardly and against the face of the jamb, instead of outwardly against the periphery thereof. The purpose of this 55 last named construction is to prevent, as far as possible, access of liquid explosive to this

part of the door. As a further preventive the terminal openings 13^a are filled with some soft metal, Babbitt, for example 13^b, thus making a continuous abutting surface. 60 The construction is such that in case it should be possible to insert a charge of explosive around the door sufficient to wreck it, the effect would be seen in the door itself, not in throwing it bodily from the safe, by 65 breaking the interlocking lugs, but by rending the door at the point of least resistance, which, as will be seen, is central to the cavity. This would, even if the outer portion were entirely dislodged, leave the inner 70 plug still in position, and presumably so jammed as to make its removal extremely difficult, if not impossible. The primary object is not, however, to provide a means for partially wrecking the door, but for protecting 75 it, by means of the air imprisoned in the cavity, against the destructive effect of an explosion, it being assumed that when such an explosion takes place at the inner shoulder of the jamb, enough of the force of 80 the explosion will be absorbed by the air-space to partially deaden the shock, and thus prevent the wrecking or dislodgment of the door.

In practice I prefer to provide the safe 85 with a simple fire-proofing jacket, so that the safe need not be set in a fire-proof vault, or inclosed in a large fire-proof safe, in order to protect it and its contents against fire. The jacket is made to conform substantially 90 to the shape of the spherical, burglar-proof safe. In order to place it in position it is made in parts, as indicated. A hemi-spherical part 16 fits over the back part of the safe and around the upper part of the base. A 95 corresponding part 17, having a central opening for the door, fits over the front part of the safe, and is joined to the rear part, preferably by a telescoping overlap 18, with suitable fastening screws 19. Between the 100 jacket and the safe are set spacing lugs 20, which may be integral parts of the jacket. At front and back the connection of the base with the safe is open, so as to permit the flow of the plastic material used for insulation, 21. At the door the jacket spacing is a circular ring 22, thus forming a part of the circular door-jamb. But little insulation is required at the door itself, and this is supplied by filling a space between the 105 web 23 of the door-frame and a circular plate 24 attached thereto, with insulating

material. The jacket being in position, the safe is turned upside down and the insulation poured in through the base which is open at the top. The opening is then closed 5 by a plate 25.

It will of course be understood that the front portion of the jacket is perforated so as to slip over the hinge lugs 12, which are necessarily longer than in safes of the ordinary type not provided with a fire-proof jacket. 10

Having thus described my invention, I claim:

1. In a burglar-proof safe, a revolute 15 door adapted to interlock with the safe, and having an internal, shock-absorbing air-space with narrow radial extensions terminating short of the periphery, and opening toward the inner end of the door.

20 2. In a burglar-proof safe, a revolute

door, having formed therein a shock-absorbing air-space with narrow extensions terminating short of the periphery, and opening toward the inner end of the door, and a filling of soft metal in said openings. 25

3. In a burglar-proof safe, a revolute door, having formed therein a shock-absorbing air-space terminating outwardly in narrow, radial extensions, unobstructed by bolts or other mechanism, the front and rear air-space walls being imperforate, and the front wall being constructed to burst at the center rather than at the sides. 30

In testimony whereof I affix my signature in presence of two witnesses.

ELLIS E. THOMPSON.
